CliC XXL Adjustable Front Magnetic Connect Expandable Reading Glasses, reviewed Aug. 2015, [online], [site visited May 26, 2020]. Available from Internet, <URL: <https://www.amazon.com/CliC-Adjustable-Magnetic-Connect-Expandable/dp/B00CFXKRM6#customerReviews>> (Year: 2015).*Primary Examiner — Sanjeev Paul(74) *Attorney, Agent, or Firm* — Alan D. Kamrath; Mayer & Williams PC(57) **CLAIM**

The ornamental design for an eyeglass magnet connection, as shown and described.

DESCRIPTION

FIG. 1 is a perspective view of an eyeglass magnet connection showing my design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof;

FIG. 7 is a bottom plan view thereof;

FIG. 8 is a sectional view thereof taken along section line 8-8 of FIG. 6; and,

FIG. 9 is a perspective view of the eyeglass magnet connection in accordance with my design, shown in its environment thereof.

The broken lines shown in FIG. 9 are included for the purpose of illustrating environment only and form no part of the claimed design.
